UNITED STATES PATENT OFFICE.

JOHN W. JONES, OF HALE, MISSOURI.

DESIGN FOR A STOVE-LEG.

SPECIFICATION forming part of Design No. 31,376, dated August 8, 1899.

Application filed July 11, 1899. Serial No. 723,503. Term of patent 14 years.

To all whom it may concern:

Be it known that I, JOHN W. JONES, a citizen of the United States, residing at Hale, in the county of Carroll and State of Missouri, 5 have invented and produced a new and original Design for a Stove-Leg, of which the following is a specification.

This invention relates to a new and original design for a stove-leg, and it has for its 10 object to provide a design of this character that shall be both useful and ornamental.

The leading feature of the design resides in a solid leg, shank, or standard approximately semicylindrical in cross-section and 15 provided with a flat inner side and an outer convexed side, said outer convexed side of the shank or standard being provided with an outwardly-swelled foot portion, whose front face is disposed at an oblique angle to the 20 inclination of the shank or standard.

The minor features of the design are the shank or standard provided with a sigmoidally-curved face at its inner side, a flat lower end, and the offstanding arm at the upper 25 end thereof.

In the drawings, Figure 1 is a perspective view of a stove-leg embodying the herein-described design. Fig. 2 is a side view of the same. Fig. 3 is a front view thereof. Fig.

30
4 is a cross-sectional view on the line 4-4 of Fig. 2.

Referring to the accompanying drawings, the numeral 1 designates an inclined solid leg or standard provided at its upper end with an angularly-disposed offstanding arm 2. 35 The said shank or standard is approximately semicylindrical in cross-section and is provided with a flat lower end 3 and at its inner side with a flat sigmoidally-curved face 4. By reason of the semicylindrical cross-sectional shape of the shank or standard the outer side thereof is convexed, and this convexed side is provided contiguous to the lower extremity of the shank or standard with an outwardly-swelled foot portion 5, having a 40 transverse rounded ridge 6, and whose face 7 is disposed at an obtuse angle to the inclination of the shank or standard.

What is claimed is—

The design for a stove-leg, herein shown 50 and described.

In testimony that I claim the foregoing as my own I have hereto affixed my signature in the presence of two witnesses.

JOHN W. JONES.
